CLAIM

We claim the ornamental design for a cornergrid system, as shown and described.

DESCRIPTION

FIG. 1 is a top, front and right side perspective view of a cornergrid system showing our new design;

FIG. 2 is a right side elevational view thereof;

FIG. 3 is a left side elevational view thereof;

FIG. 4 is a front side elevational view thereof;

FIG. 5 is a rear side elevational view thereof;

FIG. 6 is a top plan view thereof; and,

FIG. 7 is a bottom plan view thereof.

The broken line showings of the cornergrid system in the figures depict environmental subject matter and form no part of the claimed design.
